CLAIM

The ornamental design for a seal member as shown and described.

DESCRIPTION

FIG. 1 is a first perspective view of a seal member embodying the invention.

FIG. 2 is a second perspective view of the seal member of FIG. 1.

FIG. 3 is a left side view of the seal member of FIG. 1. FIG. 4 is a top view of the seal member of FIG. 1; and, FIG. 5 is a bottom view of the seal member of FIG. 1. The elements shown in broken lines are included for the purpose of illustrating environment and form no part of the claimed design.

1 Claim, 2 Drawing Sheets
